ARTHUR W. WILKINSON, OF EASTON, PENNSYLVANIA, ASSIGNOR TO STERLING PRODUCTS COMPANY, OF EASTON, PENNSYLVANIA, A CORPORATION OF PENNSYLVANIA

CONTAINER

Application filed September 27, 1932. Serial No. 635,011.

The invention relates to packages or containers for materials of various kinds and particularly for corrosive, poisonous liquids, and has for one of its objects to provide a 5 leak-proof package secure against unintentional discharge of contents, and, in a preferred embodiment of the invention, a package wherein the container in which the liquid is stored is additionally protected against 10 injury by an outer casing and is firmly held within said casing against destructive displacement, rattling, and the like. The present invention further contemplates, in its most refined form, the provision of a package 15 which is composed of a container proper and a surrounding casing which is so assembled around the container that access to the charging opening cannot be had for refilling purposes except by destruction or permanent injury of the casing. Other objects 20 of the invention and of details associated therewith will appear from the following specification.

The present invention is illustrated in connection with a package intended to contain a hydrofluoric acid containing fluid such as is used in laundry practice for the local treatment of spots and discolorations. Such liquid, on coming into contact with the skin, 30 produces very painful and injurious burns occasionally, unless promptly treated, penetrating to the bone. The acid, when coming in contact with a nail, will easily cause the loss of the nail. Instances have occurred 35 where persons have been obliged to undergo hospital treatment for periods of several months before an injury resulting from contact with such fluid was healed. It is accordingly of the utmost importance that a 40 package of this type of fluid should be absolutely leak-proof and otherwise so arranged that the operator in the use of the fluid will be able to control it without any reasonable likelihood of having the liquid make even 45 accidental contact with his hand. In order to accomplish these objects the container proper, constructed of a material such as hard rubber or other rigid material which 50 resists attack on the part of the contained fluid, is shaped and dimensioned to be held

in one hand and to be manipulated by that hand like a tool. A cylindrical chamber adapted to contain approximately five ounces or so of the fluid represents a typical size and shape. The liquid emission part of 55 the container is given the form of an extended tapered nozzle apertured for communication with the interior of the container so that the fingers of the operator, being placed about the body of the container 60 itself, will always be remote from the point of discharge of liquid from the nozzle. The nozzle element is a unitary body comprising five functional elements, (1) a threaded section adapted to cooperate with threads associated with an aperture extending through a wall of the container proper; (2) a flange adapted to cooperate with a washer seated between said flange and that part of the casing which surrounds its threaded aperture; 65 (3) a thickened or reinforced section configured to cooperate with a tool adapted to intensify the pressure of the flange upon the washer or gasket between the flange and the container; (4) a threaded or equivalent portion adapted to cooperate with a cap to securely hold the cap in place during shipment of the package or during any period when the package is not actually in use; and (5) the extended portion of the nozzle. The 70 container proper is apertured and threaded to receive the nozzle section and surrounding the outer edge of the threaded part the container is provided with a sunken seat to receive the washer or gasket and of such 75 depth that when the washer is fully compressed in place the outside face of the flange of the nozzle section is approximately flush with the outer surface of the container. A 80 cap, preferably provided with exterior irregularities to enable it to be tightened or loosened, cooperates with the fourth above identified part of the nozzle section in such 85 a way that when the cap is fully seated its 90 surface at the open end will make a continuous contact with the outer surface of the third above specified elements of the nozzle section so as to prevent the escape of fluid 95 through this joint. The inner extent of the 100

cap is approximately the same as the length of the nozzle so that when the cap is in place it will abut against the aperture at the extreme end of the nozzle and keep it closed.

- 6 The accompanying drawing illustrates by way of example a preferred embodiment of the invention. In said drawing Fig. 1 is a vertical view partly of a cross-section of a package constructed in accordance with the 10 present invention, the same being shown in assembled condition just prior to the sealing in of the casing, the container being in position within the casing and having its nozzle screwed thereon, the bottom of the casing 15 being applied thereto in the form of a blank prior to its permanent attachment to the body of the casing. Fig. 2 is a top plan view of Fig. 1. Fig. 3 is a view in elevation partly in section, showing the cap in position 20 on the nozzle and showing also the bottom of the casing attached to the cylindrical body thereof. Fig. 4 is a top plan view of Fig. 3. Fig. 5 is a top view of the empty casing, and Fig. 6 is a sectional view representing a modification of the tip and cap 25 structure of Fig. 3.

In the drawing 10 indicates a container which may be of cylindrical form, made of suitable material such as hard rubber, a 30 resinous, molded composition, or other non-metallic substance non-attackable by the fluid. The container is provided with a counter-sunk portion continued as a threaded opening 11 to receive the threaded end of a 35 nozzle 12, made of similar material. The nozzle 12 is provided with a fixed collar 13 between which and the bottom of the counter-sunk portion of the opening a washer 14 of rubber or equivalent substance is adapted 40 to be placed to insure a tight joint between the nozzle and the container. The depth of the counter-sinking and the thickness of the washer 14 and collar 13 are preferably so related that when the nozzle is screwed down 45 tight upon the container, the top of the collar is flush with the top surface of the container.

The nozzle is provided with a fixed, preferably integral non-circular or angular portion 15 illustrated as hexagonal in contour. 50 The portion 15, whatever its contour, should preferably have a maximum diameter slightly smaller than that of the collar 13. The object of the portion 15 is to provide engaging means for a wrench or tool by means of which the nozzle portion of the structure 55 may be more tightly seated upon the washer 14 than can be accomplished by hand. The washer 14, made of rubber or other compressible material not attackable by the fluid, is 60 by such means held so firmly in position that it is for practical purposes impossible to loosen the connection between the nozzle section and the container by hand or by any manipulations of the assembled device in 65 use but only by special application of a tool

and in no case by manual movement of the cap.

The nozzle 12 is preferably tapered and is provided with a discharge duct 16 which is so small as to make it extremely difficult if not practically impossible to have it emit more than the desired amount of fluid in use or to refill the container through said duct. The nozzle is also provided with a threaded portion 17 shown as located directly above the angular portion 15 for receiving a correspondingly threaded cap 18. The nozzle and cap are preferably made of the same material as the container and like the latter may be manufactured by molding. The cap shown in Fig. 3 is provided with a cushion or packing 19 of soft rubber which operates to close the duct 16 and to prevent injury to the discharge end of the nozzle when the cap is in position thereon as illustrated in Fig. 3. It is, however, preferred to incorporate in the nozzle and in the cap soft rubber tips 18a and 12a as illustrated in Fig. 6, the advantage of this construction being, first, that the soft rubber tip on the nozzle supplies a much better point with which to spread the chemical fluid over the stain on the fabric and is not so likely to injure the fabric as when a hard rubber edge bounds the mouth of the duct and, second, 80 that with a soft rubber tip on the cap as well as on the nozzle, the cap can be drawn firmly upon the nozzle and make a sure seal without requiring an extra washer with the tip.

The container is positioned within the casing 20 whose internal diameter is preferably equal to the external diameter of the container, so as to provide a snug fit. The container with the nozzle in position thereon is inserted 100 into the casing 20 through the open bottom of the latter, as illustrated in Fig. 1, and the nozzle and angular portion 15 are passed through an opening 21 in the metal cover plate 22 which is fixed to the tubular body of the casing, the opening 21 having the same outline as the angular portion or being at least so configured that relative rotary movement between the angular portion 15 and the metal plate 22 is prevented. When the container is in position within the casing, the top surface of the collar 13 bears against the under surface of the cover plate 22. As shown in Figs. 1 and 3, the top of the container or at least the portion thereof adjoining the collar 13 may be made flat in order that it may seat itself snugly against the top 110 of the casing.

Initially the container 10 is disassociated from the cap and nozzle and filled through the opening 11. The cap is then firmly screwed in place, whereupon the container is introduced into the open end of the casing 20 and the portions 15 made to protrude through the corresponding opening of the 120

5 container's metal plate 22. The container and casing being now in the position shown in Fig. 1, the cap 18 is screwed tightly upon the nozzle and a bottom plate 25 in the form of a blank is positioned against the bottom of the casing and firmly attached thereto in any suitable manner as for instance by clamping the bottom edge of the casing within the turned-over edge of the blank 25 as shown at 10 24 in Fig. 3. The bottom section 23 of the casing may be provided with a raised portion 25 which, when the bottom plate 23 is fitted against the lower edge of the casing, engages the bottom of the container. The cover 22 15 may be similarly associated with the casing, but is permanently crimped and clamped to the casing before the container is introduced into the casing. As will be seen in Fig. 1, the container is slightly longer than the normal distance between the top and bottom plates 22, 23, so that as the bottom plate is clamped to the casing, the top plate at least will be slightly flexed in an outward direction, so that the container itself is held under 20 25 resilient pressure within the casing.

25 The casing is preferably made of cardboard or the like and if desired, the metallic plates thereof may be in the form of screw caps in which event the casing may be provided with similarly threaded metallic bands at its edges. To make the casing non-operable, when the screw cap modification is used, the lower cap and its band may be soldered together or the threaded portions may, after 30 proper association with each other, be pricked to prevent rotation of the cap or caps or otherwise physically deformed to supply an effective seal which will necessitate the destruction of the seal or of the casing before 35 access can be had to the container.

40 The outer surface of the casing may contain any suitable printed matter adhesively applied thereto such as labels bearing trade marks, the name of the manufacturer, directions for use or other similar matter. The use of a cardboard casing is particularly advantageous when the container is required to be made of hard rubber or equivalent substance since labels do not readily adhere to 45 50 material such as hard rubber while they will remain in almost permanent adhesion upon a cardboard surface.

55 It will be evident that the angular portion 15 in cooperation with the correspondingly shaped walls of the opening 21 prevents unscrewing of the nozzle 12 and also prevents rotation of the container within the casing and thus serves to hold the container in fixed 60 position. The nozzle 12 cannot be removed 65 when the container is within the casing and it is consequently practically impossible for anyone to refill the container without first so damaging the casing that it cannot be used again. The improved package accordingly 70 renders it extremely difficult if not impossi-

ble for unauthorized persons to refill the same and to palm the contents off as the product of the original manufacturer.

75 The casing also serves to prevent injury to the container in that, being made of cardboard or the like, it will act not only as a reinforcement for the container but as a cushioning means reducing shocks suffered by the container when the package is shipped or dropped or otherwise subjected to rough usage.

80 The improved package is extremely simple in construction and can be manufactured at low cost. The package is so reliable that notwithstanding its extremely destructive and 85 corrosive contents it can be sent through the mails by being enclosed in an ordinary mailing tube.

90 It will be seen from the foregoing description that the invention provides a package 85 or carboy for corrosive liquids or other dangerous materials comprising a casing and a container substantially completely encased thereby, the container being provided with a nozzle projecting through the top of the 95 casing and the parts so constructed, dimensioned and interrelated that the container is held against movement within the casing and that further, in the particular form of the invention illustrated in the drawing, a package 95 is provided wherein a container is enclosed by a completely sealed casing in such a manner that access to the container cannot be had without destruction of the casing.

100 Variations from the specific form of the invention illustrated may be resorted to within the scope of the appended claims without departing from the spirit of the invention. For example, the container 10 may be provided with a separate charging opening at 105 one side of the nozzle, such opening being closed by a plug or other suitable means, in which case the nozzle 12 may be molded integrally with the body of the container, the plug lying below the top plate 22 when the 110 container and casing are assembled so as not to be reachable for refilling purposes without damage to or destruction of the casing.

I claim:

115 1. A container for corrosive liquids consisting of a supply chamber of relatively hard material, proof against attack by such liquid and of a size and shape adapted to be manipulatable by one hand alone, a seat associated with one wall of said chamber adapted to receive a washer, a threaded aperture surrounded by said seat and dimensioned for convenient filling of the chamber therethrough, a washer, a nozzle section of relatively non-breakable material, proof against corrosive 120 attack of the liquid contained in the chamber, apertured to permit passage of liquid from the chamber and having an exit duct of such small calibre as to prevent free flow of liquid therethrough, said nozzle section having 125 130

- at one end thereof a tapered nozzle extending to a point relatively remote from the apertured wall of the chamber and at the other end of the nozzle section a screwthreaded portion adapted to engage the threads of the aperture of the chamber, a flange associated with said nozzle section adapted for pressure-contact with the washer against the seat of the chamber, a relatively thick portion associated with said nozzle section adapted for engagement by a tightening tool, a cap-engaging and seating portion associated with said nozzle section, and a cap adapted to cooperate with the cap-engaging portion of the nozzle section and to be held thereby in liquid-tight position with reference to any liquid which might pass through the nozzle during the time the cap is in place.
2. A container for corrosive liquids consisting of a supply chamber of relatively hard material, proof against attack by such liquid and of a size and shape adapted to be manipulatable by one hand alone, a counter-sunk seat associated with one wall of said chamber adapted to receive a washer and a flange portion of a nozzle section, a threaded aperture surrounded by said seat and dimensioned for convenient filling of the chamber therethrough, a washer, a nozzle section of relatively non-breakable material, proof against corrosive attack of the liquid contained in the chamber, apertured to permit passage of liquid from the chamber and having an exit duct of such small calibre as to prevent free flow of liquid therethrough, said nozzle section having at one end thereof a tapered nozzle portion extending to a point relatively remote from the apertured wall of the chamber and at the other end of the nozzle section a screw-threaded portion adapted to engage the threads of the aperture of the chamber, a flange associated with said nozzle section adapted for pressure-contact with the washer against the seat of the chamber, a relatively thick portion associated with said nozzle section shaped and adapted for engagement by a tightening tool to force the flange portion against the washer into the confines of the countersunk portions of the chamber so as to be flush therewith on the exterior, a screw-thread associated with said nozzle section to operate as a cap-engaging and seating portion associated with said nozzle section, a cap adapted to cooperate with the cap-engaging portion of the nozzle section and to be held thereby in liquid-tight position with reference to any liquid which might pass through the nozzle during the time the cap is in place, and means on the exterior of the cap for affording an intensified gripping surface to aid in seating and unseating said cap, the chamber in its assembled and filled condition being so powerfully closed by the washer and nozzle section that no manual operation of the cap in
- a direction tending to unscrew the nozzle section from the chamber will be capable of loosening the connection between said nozzle section and said chamber.
3. A container for corrosive liquids of relatively hard material, a ducted nozzle projecting from its top, of relatively non-breakable material, a cardboard casing, a metal top cover associated with the top of the cylinder and having a central aperture fitting around the base portion of the nozzle, a metallic bottom cover for the cylinder, the distance between the two metallic covers when both are fully in place being so approximately equal to the height of the container that the latter is firmly and snugly held within the casing against longitudinal movement therein.
4. A container for corrosive liquids comprising a receptacle constituted of material which is not affected by the liquid, said receptacle having a charging opening and a discharge nozzle, a casing having a body of compressible material, substantially completely enclosing said container, metallic end plates for the casing, one of said end plates being provided with an opening through which said nozzle passes, and means for holding the receptacle against displacement within and with reference to the casing and its end plates.
5. A container for corrosive liquids of relatively hard material and cylindrical shape, a ducted nozzle projecting from its top, of relatively non-breakable material and having a non-circular base portion, a cardboard cylinder, a metal top cover associated with the top of the cylinder and having a central aperture fitting around the base portion of the nozzle, a metallic bottom cover for the cylinder, the distance between the two metallic covers when both are fully in place, being so approximately equal to the height of the container that the latter is firmly and snugly held within the casing against longitudinal movement therein.
6. A container for corrosive liquids, of cylindrical shape, having a top surface higher near the center than at adjacent parts, an opening at the center of its top surface and a removable ducted nozzle held in place in said opening and having portions adapted when the nozzle is fully in place to be approximately flush with the higher parts of the container and having a non-circular contoured periphery beyond said portions, a cardboard cylinder outside of the container and of approximately the same inner diameter as the exterior diameter of the container, a metal top cover permanently associated with the top end of the cylinder and having a central non-circular opening fitting the non-circular portions of the nozzle and smaller than the portions of the nozzle which are flush with the container top, so that the nozzle projects therethrough, but is not with-

drawable therethrough nor rotatable therein, a metallic bottom cover for the cylinder permanently associated with its bottom part, the space between the two covers being slightly smaller than the distance from the base of the container to its topmost surface, whereby the upper metal cover is slightly flexed centrally and in consequence holds the container under resilient pressure in the cylinder, means on the nozzle exterior of the cylinder for receiving and securely holding in place a cap for the nozzle, and a cap for the nozzle having cooperative nozzle-engaging portions and being so dimensioned that when seated the discharge aperture of the nozzle duct will be closed.

7. A container for corrosive liquids, of cylindrical shape, having a top surface higher at the center than at adjacent parts, an opening at the center of its top surface and a removable ducted nozzle held in place in said opening and having portions adapted when the nozzle is fully in place to be approximately flush with the higher parts of the container and having a non-circular contoured periphery beyond said portions, a cardboard cylinder outside of the container and of approximately the same inner diameter as the exterior diameter of the container, a metal top cover permanently associated with the top end of the cylinder and having a central non-circular opening fitting the non-circular portions of the nozzle and smaller than the portions of the nozzle which are flush with the container top, so that the nozzle projects therethrough but is not withdrawable therethrough nor rotatable therein, a metallic bottom cover for the cylinder permanently associated with its bottom part, the space between the two covers being slightly smaller than the distance from the base of the container to its topmost surface, whereby the upper metal cover is slightly flexed centrally and in consequence holds the container under resilient pressure in the cylinder, and a cap for the nozzle adapted when in place thereon to close the discharge aperture of the nozzle duct.

8. A container for corrosive liquids, of cylindrical shape, having an opening at the center of its top surface and a removable ducted nozzle held in place in said opening and having portions adapted when the nozzle is fully in place to be approximately flush with the higher parts of the container and having a non-circular contoured periphery beyond said portions, a cardboard cylinder outside of the container and of approximately the same inner diameter as the exterior diameter of the container, a metal top permanently associated with the top end of the cylinder and having a central non-circular opening fitting the non-circular portions of the nozzle and smaller than the portions of the nozzle which are flush with the container top, so that the nozzle projects therethrough but is not

withdrawable therethrough nor rotatable therein, a metallic bottom cover for the cylinder permanently associated with its bottom part, a cap for the nozzle adapted when in place thereon to close the discharge aperture of the nozzle duct.

9. A container for corrosive liquids, having an opening in its top surface and a removable ducted nozzle held in place in said opening and having portions adapted when the nozzle is fully in place to be approximately flush with the adjoining parts of the container and having a non-circular contoured periphery beyond said portions, a cardboard tube outside of the container and snugly fitting the same, a metal top cover permanently associated with the top end of the tube and having a non-circular opening fitting the non-circular portions of the nozzle and smaller than the portions of the nozzle which are flush with the adjoining surface of the container top so that the nozzle projects therethrough but is not withdrawable therethrough nor rotatable therein, a metallic bottom cover for the cylinder permanently associated with its bottom part, and a cap for the nozzle adapted when in place thereon to close the discharge aperture of the nozzle duct.

10. A container for corrosive liquids, having a top surface higher near the center than at adjacent parts, an opening at the center and a removable ducted nozzle held in place in said opening, a cardboard cylinder outside of the container and of approximately the same inner diameter as the exterior diameter of the container, a top cover permanently associated with the top end of the cylinder and having a central opening through which the nozzle projects, a bottom cover for the cylinder permanently associated with its bottom part, the space between the two covers being slightly smaller than the distance from the base of the container to its topmost surface, whereby the upper metal cover is slightly flexed centrally and in consequence holds the container under resilient pressure in the cylinder, and means associated with the nozzle and adapted to prevent its removal when the container is encased within the closed cylinder.

11. A container for corrosive liquids having a top surface higher near the center than at adjacent parts, an opening at the center and a removable ducted nozzle held in place in said opening, a tube outside of the container and snugly fitting the same, a top cover permanently associated with the top of the cylinder and having an opening arranged to receive said nozzle, a metallic bottom cover for the tube permanently associated with its bottom part, the space between the two covers being slightly smaller than the distance from the base of the container to its topmost surface, whereby the upper cover is slightly flexed and in consequence holds the container

under resilient pressure in the tube, and means associated with the nozzle and adapted to prevent its removal when the container is encased within the closed tube.

- 5 12. A container such as described in claim 1, in which the outermost forward part of the nozzle is constituted of resilient material, and a cap is positioned over said nozzle, the inner longitudinal extent of said cap being 10 such as to cause compression to be exerted upon said resilient tip of the nozzle by the closed inner end portion of the cap.

- 15 13. A container such as described in claim 1, in which the outermost forward part of the nozzle is constituted of resilient material, and a cap, the closed inner portion of which is also constituted of resilient material, is positioned over said nozzle, the inner longitudinal extent of said cap being such as to 20 bring the two resilient sections into compressive contact with each other.

In testimony whereof I have hereunto set my hand.

ARTHUR W. WILKINSON.
